UNITED STATES PATENT OFFICE.

WALTER CLAUDE JOHNSON, OF COLEMANS HATCH, ENGLAND.

WATER-DISTRIBUTER.

No. 928,386.

Specification of Letters Patent.

Patented July 20, 1909.

Application filed February 6, 1909. Serial No. 476,513.

To all whom it may concern:

Be it known that I, WALTER CLAUDE JOHNSON, subject of the King of Great Britain, residing at Broadstone Farm, Colemans 5 Hatch, county of Sussex, England, have invented a new and useful Improved Water-Distributer, of which the following is a specification.

The present invention consists in an improvement on the water distributor described in the specification of my previous patent No. 902,662.

In the water distributor therein described the nozzle is uniformly rotated while it undergoes a gradual alteration in its inclination to the vertical, the water being normally projected in an upwardly inclined direction although it is mentioned that the distributor may alternatively be affixed to the ceiling 20 of a room in an inverted manner so as to operate as a fire-extinguisher.

For fire extinguishing purposes it is important that the jet of water should play upon the ceiling of the room as well as the 25 walls and floor thereof and articles inclosed therein.

Accordingly, the present invention consists in so mounting and actuating the nozzle that it is caused to continuously rotate about 30 an axis which is inclined in a downward direction relatively to the horizontal plane the nozzle being deviated from the line of the axis and the said inclined axis being caused to continuously rotate about a vertical axis.

35 In order that the invention may be more easily understood a constructional form is illustrated on the accompanying drawing, in which:—

Figure 1 is a vertical section, and Fig. 2 an 40 inverted plan.

The distributor comprises a casing *a* adapted to be secured to a ceiling in an inverted manner, and provided with a screw-threaded nipple *b* for connection to a water 45 service pipe. A vaned wheel *c* is rotatably mounted within the casing *d* and water under pressure, admitted by the nipple *b*, is directed on to the vanes and effects the rotation of the wheel *c*.

50 The wheel *c* by means of a train of wheels *c¹*, *c²*, *d¹* and *d²* drives a pair of spur-wheels *e* *f*. One of the spur-wheels *e* is secured to a hollow shaft *g* which is journaled in the casing *a*, while the other spur-wheel *f* is freely 55 mounted to revolve co-axially with *c*. The

wheel *f* is also provided with a crown of bevel-teeth *d*.

The spur-wheel *e* is provided with a tubular extension *c¹* which serves, on the escape of the water from the wheel *c* through the 60 hollow shaft *g*, to deviate it in a downwardly inclined lateral direction the line of which rotates about a vertical axis through the center of the machine.

To the extremity of the tubular extension *c¹* a hollow shaft *i* is secured which forms a journal for a bevel wheel *j* which gears with the before mentioned bevel-teeth *h* of the spur-wheel *f*.

To the boss of the bevel-wheel *j* the nozzle 70 *k* is secured, the center line of the extremity of the nozzle diverging from the axis of the hollow shaft *i* and bevel-wheel *j* in such a manner that on the revolution of the bevel-wheel *j* around the shaft *i* the escaping water 75 will be projected as from the apex of a cone along a slowly revolving generating line.

The pair of spur-wheels *e* *f* have an unequal number of teeth, whereby, on their rotation by the pinion *d²*, one will lag relatively 80 to the other and cause the slow rotation of the nozzle *k*. Thus, while the spur-wheel *e* will carry the axis of the bevel-wheel *j* around a vertical line, the cranked nozzle *k* itself will be caused to slowly and continuously 85 rotate about the said axis. By such means the nozzle will be gradually directed in a manner to cause the jet to play in succession upon all portions of a room including the ceiling. 90

I claim.

1. In a water distributor, a nozzle, means for slowly rotating said nozzle about a laterally extending axis inclined thereto and means for rotating said axis about a vertical 95 axis at a rate which is a high multiple of the rate of rotation of said nozzle.

2. In a water distributor, a casing, a water-supply nipple thereon, a vaned wheel located in said casing, a pair of differential 100 spur-wheels rotatably mounted on said casing, gearing connecting said vaned wheel with said spur-wheels, a crown of bevel-teeth provided on one of said spur-wheels, an inclined nozzle rotatably mounted on the other spur-wheel about a laterally inclined axis and a bevel wheel secured to said nozzle and gearing with said bevel-crown. 105

3. In a water distributor, a casing, a water supply nipple thereon, a vaned wheel located 110

in said casing, a hollow shaft rotatably mounted on said casing, a spur-wheel rotatably mounted on said hollow shaft, a crown of bevel-teeth provided on said spur-wheel, 5 secured to said hollow shaft, a second spur-wheel having a different number of teeth to said first spur-wheel, gearing connecting said vaned wheel with said spur-wheels, a laterally inclined tubular extension provided on 10 said second spur-wheel, a bevel-wheel rota-

tably mounted on said tubular extension and gearing with said bevel-crown and an inclined nozzle secured to said bevel wheel.

In testimony whereof I have signed my name to this specification in the presence of ^{is} two subscribing witnesses.

WALTER CLAUDE JOHNSON.
